UNITED STATES PATENT OFFICE.

HENRY BARNHARD FURSTONBURG, OF SHREVEPORT, LOUISIANA.

LATERAL-TAKE-UP DEVICE FOR LOCOMOTIVE-AXLES.

1,344,267.

Specification of Letters Patent. Patented June 22, 1920.

Application filed January 30, 1918. Serial No. 214,461.

To all whom it may concern:

Be it known that I, HENRY B. FURSTONBURG, a citizen of the United States, and a resident of Shreveport, in the parish of 5 Caddo and State of Louisiana, have made certain new and useful Improvements in Lateral-Take-Up Devices for Locomotive-Axes, of which the following is a specification.

10 My present invention relates generally to railway appliances, and more particularly to a device for taking up the lengthwise thrust of locomotive axles, my object being the provision of an improved construction 15 along the lines of my Patent 1,202,701, granted October 24, 1916.

In my patent just referred to, inner and outer take up sections were described and claimed adjacent each of the driving boxes, 20 the inner sections at each side being keyed or otherwise fastened to the axle, and the two sections having abutting flanges, upon disconnection of which, the outer and movable section might be adjusted with respect 25 to the inner stationary section.

In my present improvements I purpose to avoid the expense of inner sections formed in the manner shown in my patent, and to substitute therefor collars united to 30 the axle in such a manner as to form substantially a part thereof, the collars themselves taking the place not only of the inner sections of the Patent 1,202,701, before referred to, but of the flanges as well, as the 35 collars present effective means in opposition to the inner flanges of the outer sections, which latter may be constructed substantially like those shown in my patent referred to.

40 In the accompanying drawing forming part of this invention:—

Figure 1 is an elevation of a portion of an axle equipped with my present improvements, partly broken away and in section.

45 Fig. 2 is a transverse section through one of the collars, and,

Fig. 3 is a face view thereof showing a sectional form.

Referring now to these figures, my improvements, as in my patent referred to above, are installed and utilized in connection with a locomotive axle A, at a point spaced on which, with respect to its driving boxes, of 50 which one appears at B, in Fig. 1, in turn adjacent the wheel C, my invention purposes the connection of an annular collar 10 hav-

ing a sharply tapered opening whose point of smallest diameter adjacent one side of the collar is slightly greater than the diameter of the axle A, so as to admit of disposal of 60 the collar on the shaft in the position shown in Fig. 1.

If the collar 10 is disposed upon the axle A in the first instance, or where it is necessary to dismantle the axle assemble for other 65 reasons, a collar in one piece is utilized. On the other hand, as shown in Fig. 3, the collar may consist of segments 10^a, so that they may be placed circumjacent the axle without dismantling the parts carried thereby, 70 the abutting ends of these segments being welded, fused or otherwise connected to form an integral one piece structure at the same time and possibly by the same means utilized as presently described for connecting the 75 collar to the axle.

The taper of the opening through the collar 10 provides for the convenient reception of a fusing metal 11, which is caused to flow into the space between the collar and the 80 axle as seen in Fig. 1, fusing the collar to the axle and connecting and supporting the same in substantially an integral manner thereto.

As seen in Figs. 2 and 3, moreover, the 85 collar 10 has openings 12 therethrough for the reception of bolts 13, as seen in Fig. 1, which connect the collar to the inner flange 14 of its respective adjustable section 15, the latter having an outer flange 16 opposing 90 the inner face of the driving box B, and being in segments having longitudinal flanges 17 connected by bolts 18.

It is obvious therefore, that by disconnecting the inner flange 14 of the outer section 15 from the collar 10, the outer section 15 may be adjusted toward the driving box B to take up any play resulting from undue wear, and that spacers, liners, or other devices of similar nature may be inserted between the collar 10 and the flange 14 and the bolts 13 thereafter reintroduced to again rigidly connect the adjustable section 15 in adjusted position.

It is obvious, therefore, that the strain 105 upon the collar 10 is in a direction away from the adjustable section 15, and to this end the collar may be further braced in its connected relation to the axle A by the utilization of triangular bracing members 19 110 in spaced relation around the axle A, whose right angular faces are welded, fused or

otherwise joined to the axle A and to the inner side face of the collar 10.

It is apparent that in the manner above described I am enabled to dispense with the more costly inner sections of my Patent 1,202,701, before referred to and at the same time produce the same effective results.

I claim:—

- 10 1. A lateral take up device for locomotive axles comprising an adjustable section and a stationary abutment section, said abutment section being in the form of a collar provided with a tapered opening through which the axle extends, a fusing metal in the space within said collar formed by said tapering opening around the shaft to rigidly connect the collar with the shaft, means for connecting the adjacent portions of the collar and said adjustable section, and triangular bracing members disposed in spaced relation around the axle and connected to the latter and to the inner face of the collar for the purpose described.
- 15

tions of the collar and said adjustable section.

- 20 2. A lateral take up device for locomotive axles comprising an adjustable section and a stationary abutment section, said abutment section being in the form of a collar provided with a tapered opening through which the axle extends, a fusing metal in the space within said collar formed by said tapering opening around the shaft to rigidly connect the collar with the shaft, means for connecting the adjacent portions of the collar and said adjustable section, and triangular bracing members disposed in spaced relation around the axle and connected to the latter and to the inner face of the collar for the purpose described.
